UNITED STATES PATENT OFFICE.

GEORGE S. BLAKESLEE, OF CHICAGO, ILLINOIS.

MACHINE FOR WASHING BOXES, CANS, AND OTHER ARTICLES.

1,423,300.

Specification of Letters Patent.

Patented July 18, 1922.

Application filed February 23, 1917. Serial No. 150,474.

To all whom it may concern:

Be it known that I, GEORGE S. BLAKESLEE, a citizen of the United States, and a resident of Chicago, in the county of Cook and State of Illinois, have invented certain new and useful Improvements in Machines for Washing Boxes, Cans, and Other Articles, of which the following is a specification, reference being had to the accompanying drawings.

My invention relates to washing machines, and particularly to machines for washing metallic shipping and storing vessels of various kinds, such as biscuit cans, although it may be used for washing a great variety of articles. It will be understood, therefore, that while I have illustrated and hereinafter described my improved machine with special reference to its use for washing square cans such as those commonly used for packing biscuits or crackers, my invention is not limited to use for such purposes only, but contemplates the use of the apparatus shown and described for any purpose for which it is adapted.

Ordinarily, cans or vessels of the character referred to are made of tin and are provided with a hinged cover, and as they must be thoroughly washed on the inside as well as on the outside and must also be completely dried to prevent rusting, several important factors must be taken into consideration in providing a suitable machine for washing and drying them. First, the cover must be held out of the way so as to permit free access of the wash-water to the interior of the can. Second, the cover must be held so that it will not be damaged or the hinges injured. Third, provision must be made for violently throwing the wash-water and the rinsing water not only over the outside of the can and cover but also into the interior of the can. Fourth, the can must be so held as to permit the washing and rinsing water to drain out freely. Fifth, the can and cover must be completely dried both inside and outside. Sixth, the mechanism for moving the cans through the washing and drying apparatus must be so constructed and arranged as not to interfere with the thorough washing and drying of the cans and covers. In my pending application, Serial No. 92,387, filed April 20, 1916, I have shown and described a machine of the same general character as that of this application, the principal differences between them having to do

with the arrangement of the drying compartment, the mechanism by which the drying is accomplished, the provision in the machine of the latter application of means for disposing of the vapors arising in the cleansing compartments, and the construction and arrangement of the conveying mechanism. Both machines, however, meet the requirements of a successful apparatus for the purpose stated.

In the accompanying drawings, which illustrate the preferred embodiment of my invention,—

Fig. 1 is a side elevation;

Fig. 2 is a plan view thereof;

Fig. 3 is a horizontal sectional view of the left-hand end of the machine as illustrated in Fig. 1, showing the conveyer mechanism and the washing and rinsing paddle-wheels, together with the housing which encloses the apparatus;

Fig. 4 is a continuation to the right of Fig. 3,—these two figures taken together forming a horizontal sectional view of the whole machine;

Fig. 5 is a partial vertical section of that portion of the machine shown in Fig. 4, illustrating the mechanism used for drying the cans;

Fig. 6 is a vertical cross-sectional view, illustrating the general construction of the inlet end portion of the machine—that is to say, that portion in which are located the washing and rinsing mechanism and the mechanism for controlling the circulation of air and vapor;

Fig. 7 is a reduced cross-sectional view of the discharge or drying end of the machine;

Fig. 8 is an enlarged detail illustrating a part of the conveying mechanism; and

Fig. 9 is a fragmentary view illustrating the support upon which the open end of the can rests while being washed and dried.

Referring to the drawings,—

10—11 indicate two tanks adapted to hold washing and rinsing water, respectively, said tanks being separated by a partition 12 and having, respectively, end partitions 13—14. 15—16 indicate compartments arranged at one side of the washing and rinsing tanks, respectively, and opening thereinto. The bottoms of said compartments are at a higher level than the bottoms of the tanks 10—11, as shown in Fig. 6, so that the solid matter washed from the cans may settle at the bottom of the washing and rinsing tanks and

will not pass into the compartments 15—16. 17—18 indicate washing and rinsing paddle-wheels mounted in the compartments 15—16, respectively, and adapted by their rotation 5 to violently throw the washing and rinsing water upwardly and laterally into the upper portions of the washing and rinsing chambers. In the views illustrated, the paddle-wheels 17—18 rotate in a clockwise direction. 10 19—20 indicate housings which enclose the paddle-wheel compartments 15—16, said housings merging in a housing 21 which encloses the entire machine and also the washing and rinsing tanks. This housing is 15 mounted on legs or other suitable supports 22, as best shown in Fig. 1. 23 indicates a shaft mounted in suitable bearings carried by the housings 19—20, the paddle-wheels 17—18 being mounted on said shaft, as 20 shown in Fig. 3. The shaft 23 is driven from an electric motor 24 mounted on the top of the housing 21, as shown in Fig. 1, said motor having a pulley 25 connected by a belt 26 with a pulley 27 mounted on a 25 counter-shaft 28 also journaled in suitable bearings in the housings 19—20, as shown in Fig. 1. The shaft 28 is geared to the shaft 23 by a pinion 29 mounted on the shaft 28 and a gear 30 mounted on the shaft 23, as shown. 31—32 indicate rails which extend longitudinally of the machine over the washing and rinsing compartments and through the drying compartment herein- 30 after described, which is a horizontal extension of the washing and rinsing compartments. In the construction shown, these rails are suitably spaced apart so as to be adapted to support the cans or other articles to be washed, and as shown in Fig. 6, 35 40 the rail 31 is an angle-iron and the rail 32 is a channel-iron, the latter having an inner marginal flange 33 and a higher outer flange 34, as best shown in Figs. 6 and 9. Adjacent to the flange 33 the rail 32 is also provided 45 with perforations 35 at suitable intervals for the escape of drippings, as hereinafter described. Both these rails are carried on supporting cross bars 36 mounted at suitable intervals longitudinally of the machine 50 by means of brackets 37—38, as shown in Fig. 6. The cross-bars 36 are in the form of angle-bars, their vertical flanges being fitted in slots in the brackets 37—38 so that they may readily be removed when desired. 55 They are also so mounted or shaped that the rail 32 is carried at a somewhat lower level than the rail 31 so that the cans are supported in an inclined position, as shown in Figs. 6 and 7, the open ends of the cans 60 being toward the washing and rinsing compartments. As best shown in Fig. 6, the rails 31—32 are mounted a short distance above the normal water level in the washing and rinsing tanks so that as the cans move 65 past the washing and rinsing paddle-wheels

the washing or rinsing water will be thrown violently into them and around them, and will drain back into the washing and rinsing tanks owing to the inclination of the cans. It will also be apparent that after the bulk 70 of the washing and rinsing water flows out of the can, the drippings will also flow down and out into the channel-iron track 32 and will be returned to the washing and rinsing tanks through the drip holes 35. 39 indicates an overhead rail which is secured to the top of the housing 21 and extends longitudinally thereof over the cans and in close proximity thereto so as to prevent displacement thereof during the washing and rinsing 80 operations. Said rail, in the construction shown, is mounted on brackets 40 placed at suitable intervals.

41 indicates the drying compartment, which, as has been stated, is an extension of 85 the washing and rinsing compartments, the drying compartment being separated therefrom by a cross partition 42, having an opening for the passage of the cans, as best shown in Figs. 3 and 6. This partition prevents 90 the rinsing water from splashing into the drying compartment and aids in maintaining the proper movements of air and vapors in the different compartments. 43 indicates a bank of steam pipes arranged in the lower 95 portion of the drying compartment, as best shown in Fig. 5, said steam pipes having connections 44—45 so that steam may be caused to circulate therethrough from any suitable 100 source. 46 indicates a baffle-plate which ex- 100 tends over the steam pipes 43 and under the rails 31—32, as also shown in said figure. The baffle-plate 46 does not extend quite to the ends of the drying compartment 41, its 105 purpose being to direct the air currents to- 105 wards the ends of the drying compartment, as hereinafter described. 47 indicates a hot air pipe which extends longitudinally of the 110 drying compartment at one side thereof, as shown in Figs. 1 and 2, said pipe having a 110 number of nipples 48 which open into the 115 drying compartment at intervals, as illus- 115 trated in Figs. 2 and 7. These nipples are located so as to direct hot air into the open 120 ends of the cans as they move along through 120 the drying compartment, as shown in the latter figure. Preferably, the pipe 47 tapers 125 toward the discharge end of the machine so as to equalize the distribution of the hot air throughout the length of the drying com- 125 partment. 49 indicates an exhaust pipe which opens into the lower portion of the 130 drying compartment below the steam pipes 43 and baffle-plate 46, as shown in Fig. 5. The latter pipe connects with the inlet side 125 of a fan or blower 50, and the pipe 47 con- 130 nects with the outlet side of said fan, as shown in Fig. 6. Thus, when the fan is in operation, air is drawn into the pipe 49 from the lower portion of the drying compartment, 130

passing over the steam pipes 43 and around the baffle-plate 46 in its course to said pipe. At the same time, the heated air so withdrawn from the drying compartment is reintroduced into the upper portion thereof through the pipe 47 and nipples 48, being discharged into the interior of the cans, as above described. Thus, a constant circulation of hot air is maintained through the 10 drying compartment, such hot air being discharged directly into the interior of the cans so that they are quickly and completely dried. The fan 50 is also driven from the motor 24 by means of a belt 51 which passes 15 around a pulley 52 mounted on the lower shaft 53, as shown in Fig. 6, said belt being driven by a pulley 54 mounted on the shaft 28, as shown in Fig. 1.

55—56 indicate exhaust pipes which connect from above with the end portions of the washing and rinsing compartments, respectively, by hoods 57—58, as shown in Figs. 1 and 2. The hood 57 is adjusted to the inlet end of the machine, and the hood 25 58 is adjusted to the partition 42. The two exhaust pipes 55—56 connect with a common pipe 59 which leads to an exhaust fan 60 mounted on top of the machine, as shown in Fig. 1, being arranged to discharge 30 through a pipe 61. Thus, while the exhaust fan 60 is in operation the vapors rising in the washing and rinsing compartments will be drawn off and discharged through the pipe 61, thus preventing them 35 from passing into the drying compartment, and insuring the preservation of the air in the drying compartment in a state of dryness. The exhaust fan 60 is operated from the shaft 28 by a belt 62 driven by a pulley 40 63, as shown in Fig. 1.

The cans or other articles are moved through the machine by a conveyer the construction of which is best shown in Figs. 4, 6 and 8. Said conveyer comprises a link belt or chain 64 having at intervals a series of vertically-disposed plates 65, the ends of said plates being fitted in grooves in upper and lower tracks 66—67, respectively, so that the plates 65 are adapted to travel in 50 a vertical position longitudinally of said tracks. The tracks 66—67 are secured against the side wall of the housing opposite that at which are located the washing and rinsing paddle-wheels and above the 55 level of the cross-bars 36, as shown in Fig. 6. By mounting the conveyor at the opposite side of the cleansing compartments from the paddle wheels, the water thrown by said wheels has unobstructed access to the 60 cans or other articles, and may pass freely over the same, so that their proper cleansing is assured. 68—69 indicate a second pair of tracks, corresponding with the tracks 66—67, the tracks 68—69 being located outside of the 65 housing of the machine and being support-

ed by brackets 70, as best shown in Figs. 6 and 7. The chain or belt 64 is endless, and the two pairs of tracks 66—67 and 68—69 thus provide for supporting said chain as it travels. 71 indicates horizontally-projecting arms which are carried by the plates 65 and extend transversely of the machine in position to engage the cans resting on the rails 31—32. Each of said arms is provided at its outer end with a rearwardly-extending finger 72, as shown in Fig. 4, said finger being so placed as to form a support against which the lid of the can may rest when turned back at right angles with the body of the can, thus holding the lid in such position and preventing it from being swung backward far enough to damage the hinge; it also supports the lid against the impact of the wash-water, and prevents it from being distorted in shape. 73 indicates the cans. 74 indicates a longitudinally-extending table which extends laterally from the housing 21 and is supported by braces 75, as shown in Fig. 6. This table is designed to support the cans after they are removed from the machine, and it also overlies the returning portion of the conveyer so as to guard the arms 71 as they move back toward the inlet end of the machine. 76—77 indicates sprocket-wheels mounted at the ends of the machine for supporting the end portions of the chain 64, as best shown in Figs. 3 and 4. One of said sprocket-wheels, as 76, is mounted in bearings adjustable longitudinally by means of a screw 78 so that the tension of the conveyer 64 may be regulated. The conveyer is driven from the motor 24 through the shaft 23 which is provided with a worm 79 which engages with a worm-wheel 80 mounted on a shaft 81 which also carries a beveled pinion 82, as shown in Fig. 3. The latter pinion meshes with a beveled pinion 83, carried by a longitudinally-extending shaft 84 supported by 100 brackets 85, as shown in Fig. 1. At the discharge end of the machine the shaft 84 carries a beveled pinion 86 which meshes with a beveled pinion 87 mounted on a transverse shaft 88, which, at its opposite 105 end, carries a second beveled pinion 89. The latter pinion meshes with a beveled pinion 90 mounted on a vertical shaft 91 which also carries the sprocket-wheel 77, as shown in Fig. 4. Thus, the conveyer travels continuously so as to move the cans longitudinally of the machine without being handled, first past the washing and rinsing compartments and then through the drying compartment, after which they are removed 110 by the attendant. 92 indicates a partition at the inlet end of the machine, which partly encloses such end, leaving sufficient space for the admission of cans. As best shown in Fig. 5, a similar partition 94 is provided 115

at the outlet end of the machine. Thus, the machine is practically completely enclosed so that the desired circulation of air and the withdrawal of the vapors may be effectively accomplished.

While I have described with considerable particularity the construction of the machine illustrated, it will be understood that my invention is not limited to the specific construction shown except in so far as such construction is specifically claimed. Any suitable means, such as steam pipes, may be used for heating the washing and rinsing water.

That which I claim as my invention, and desire to secure by Letters Patent, is,—

1. A washing machine of the character described comprising a housing substantially enclosing a cleansing compartment, means for supporting cans having hinged covers and for supporting the covers in open position as the cans pass through the cleansing compartment, a tank, and a paddle wheel at one side of the cleansing compartment operating to throw water from said tank into and around the cans.

2. A washing machine of the character described comprising a housing substantially enclosing a cleansing compartment, means for supporting in an inclined position cans having hinged covers and for supporting the covers in open position as the cans pass through the cleansing compartment, a tank, and a paddle wheel at one side of the cleansing compartment operating to throw water from said tank into and around the cans.

3. A washing machine of the character described comprising a housing substantially enclosing a cleansing compartment, means for supporting the articles to be cleansed in an inclined position as they pass through the cleansing compartment, a tank, a paddle wheel at one side of the cleansing compartment operating to throw water from said tank into and around the articles to be washed, and means at the opposite side of said housing from said paddle wheel for moving the articles through the cleansing compartment.

4. A washing machine of the character described comprising a housing substantially enclosing a cleansing compartment, means for supporting in an inclined position cans having hinged covers and for supporting the covers in open position as the cans pass through the cleansing compartment, a tank, a paddle wheel at one side of the cleansing compartment operating to throw water from said tank into and around the cans, and means at the opposite side of said housing from said paddle wheel for moving the cans through the cleansing compartment.

5. A washing machine of the character described, comprising a cleansing compartment, tracks extending through said compartment,

the track at one side of said compartment being in the form of a channel-bar with its inner flange lower than its outer flange, said tracks being arranged to support cans in an inclined position, and means at one side of the machine operating to throw water upward into and around the cans as they pass through said compartment.

6. A washing machine of the character described, comprising a cleansing compartment, tracks extending through said compartment, the track at one side of said compartment being in the form of a channel bar with its inner flange lower than its outer flange, said channel-bar having openings for the escape of drippings, said tracks being arranged to support cans in an inclined position, and means at one side of the machine operating to throw water upward into and around the cans as they pass through said compartment.

7. A washing machine of the character described, comprising a cleansing compartment, a tank, a paddle-wheel at one side of said compartment operating to throw a mass of water from said tank diagonally upward against and over the articles to be cleansed as they pass through said cleansing compartment, an endless conveyor for moving cans having covers hinged thereto through said compartment, said conveyor being mounted to operate in a substantially horizontal plane, means for supporting the cans during their movement through the compartment, tracks at the opposite side of said cleansing compartment from said paddle-wheel for supporting said conveyor, substantially horizontal arms carried by said conveyor and adapted to engage the cans and move them through the cleansing compartment and means for supporting the can covers in an open position.

8. A washing machine of the character described, comprising a cleansing compartment, a tank, a paddle-wheel at one side of said compartment operating to throw a mass of water from said tank diagonally upward against and over the articles to be cleansed as they pass through said cleansing compartment, an endless conveyor mounted to operate in a substantially horizontal plane, tracks at the opposite side of said cleansing compartment from said paddle-wheel for supporting said conveyor, substantially horizontal arms carried by said conveyor and adapted to engage the articles to be cleansed and move them through the cleansing compartment, and means for supporting the articles to be cleansed as they are moved through said cleansing compartment by said conveyor.

9. A washing machine of the character described, comprising a cleansing compartment, a tank, a paddle-wheel at one side of said compartment operating to throw a

mass of water from said tank diagonally upward against and over the articles to be cleansed as they pass through said cleansing compartment, an endless conveyor mounted 5 to operate in a substantially horizontal plane, tracks at the opposite side of said cleansing compartment from said paddle-wheel for supporting said conveyor, substantially horizontal arms carried by said 10 conveyor and adapted to engage the articles to be cleansed and move them through the cleansing compartment, means for supporting the articles to be cleansed during their movement through the compartment, and 15 return tracks for said conveyor located outside of said housing.

10. A washing machine of the character described, comprising a cleansing compartment, a tank, a paddle-wheel at one side of 20 said compartment operating to throw a mass of water from said tank diagonally upward against and over the articles to be cleansed as they pass through said cleansing compartment, an endless conveyor for moving cans 25 having covers hinged thereto through said compartment, said conveyor being mounted to operate in a substantially horizontal plane, oppositely disposed upper and lower tracks at the opposite side of said cleansing 30 compartment from said paddle-wheel for supporting said conveyor, substantially horizontal arms projecting away from said conveyor and adapted to engage the cans and move them through the cleansing compartment, said arms having means for supporting the can covers in an open position, means 35 for supporting the cans as they are moved through said cleansing compartment by said conveyor, and return tracks for said conveyor located outside of said housing.

11. A washing machine of the character described, comprising a housing forming a cleansing compartment, a tank, a paddle-wheel at one side of said compartment operating to throw a mass of water from said tank diagonally upward against and over the articles to be cleansed as they pass through said cleansing compartment, an endless conveyor mounted to operate in a substantially horizontal plane, oppositely disposed upper and lower tracks at the opposite side of said cleansing compartment from said paddle-wheel for supporting said conveyor, substantially horizontal arms projecting away from said conveyor and adapted to engage the articles to be cleansed and move them through the cleansing compartment, return tracks for said conveyor located

outside of said housing, and a plate connected with the housing and overlying and 60 protecting the return portion of the conveyor and the arms thereof.

12. A washing machine of the character described, comprising a cleansing compartment, a conveyor for moving cans having 65 covers hinged thereto through said compartment, means carried by said conveyor for supporting the can covers substantially upright in an open position as the cans are moved through said compartment, and 70 means for throwing water against said cans and covers.

13. A washing machine of the character described, comprising a cleansing compartment, a conveyor for moving cans having 75 covers hinged thereto through said compartment, arms carried by said conveyor and engaging the cans, means carried by said arms for supporting the can covers substantially upright in an open position as the cans 80 are moved through said compartment, and means for throwing water against said cans and covers.

14. A washing machine of the character described, comprising a cleansing compartment, a tank, a paddle-wheel at one side of said compartment and operating to throw a mass of water from said tank against and over the articles to be cleansed, a conveyor adapted to conduct cans having hinged covers in an inclined position through said cleansing compartment with the open ends of said cans toward said paddle-wheel, and means for supporting the can covers substantially upright in an open position against 85 the impact of the cleansing water as the cans move along through the cleansing compartment.

15. A washing machine of the character described, comprising a cleansing compartment, a tank, a paddle-wheel at one side of said compartment and operating to throw a mass of water from said tank against and over the articles to be cleansed, a conveyor adapted to conduct cans having hinged covers in an inclined position through said cleansing compartment with the open ends of said cans toward said paddle-wheel, stationary means supporting said cans as they are moved along by said conveyor, and 105 means for supporting the can covers substantially upright in an open position against the impact of the cleansing water as the cans move along through the cleansing compartment.

GEORGE S. BLAKESLEE.
